UNITED STATES PATENT OFFICE.

JOHN NONNENBACHER, OF NEW YORK, N. Y.

DESIGN FOR MOLDINGS FOR PICTURE-FRAMES, &c.

Specification forming part of Design No. 6,959, dated October 14, 1873; reissue No. 5,986, dated July 24, 1874; application filed May 1, 1874.

To whom it may concern:

It is known that I, JOHN NONNENBACHER, of the city, county, and State of New York, invented a Design for Molding to be used for Picture-frames, Cornices, &c., of which the following is a specification: The nature of my design is fully illustrated in Figure 2 of the accompanying drawing, which represents a cross-section giving an outline thereof, to which reference is made. *a* represents a portion of the molding, with the top brought well forward. *b* represents a convex portion of the molding. *c* represents a recess and concave portion of the molding. *d* represents a slightly-convex part of the molding, sunk. The other parts of the molding are clearly defined in Fig. 3 of the drawing, which represents the design as a hole, and which may be varied in some of the minor and unimportant details without substantially changing the design or altering the general effect when viewed at a little distance.

Fig. 1 represents a face-elevation of my design for a molding, with its members ornamenteed—that is to say: *a*, with rusticated staff, raised and in gilt; *b*, with raised ornaments, as shown, in gilt; *c*, with a smooth surface and having a flat ornamentation, the ground being silvered over the gilt, leaving the ornament in bright gilt. All the re-

maining members or parts of the molding, as shown, are in silver gilt.

The ornaments, as above described, as well as the color, in gilt or otherwise, of the several parts or members, may be slightly varied or imitated without changing the character of the general design, as shown in No. 2, or the effect upon the eye of the molding when finished and ready for use, as seen from a distance at which moldings in use are usually observed.

I do not claim the several forms of molding, separately and individually considered, which have been assembled together to make up the design shown in Fig. 2, which may be composed of more or less parts or pieces of wood or other material, according to the economy of manufacture may be served; but

What I do claim is—

1. The design of a molding for frames, cornices, &c., as shown in Fig. 2 of the drawing.
2. The design for the face of stripe C', as shown.
3. The design for the face of stripe D, as shown.
4. The design for the face of the molding, as shown in Fig. 1 of the drawing.

JOHN NONNENBACHER.
